J. D. MURRAY

PAINT GUN

Filed Nov. 10, 1922

Inventor.
John D. Murray

By *W. W. Miller*
Attorney.

UNITED STATES PATENT OFFICE.

JOHN D. MURRAY, OF SAN FRANCISCO, CALIFORNIA.

PAINT GUN.

Application filed November 10, 1922. Serial No. 599,994.

To all whom it may concern:

Be it known that I, JOHN D. MURRAY, a citizen of the United States, residing in the city and county of San Francisco and State 5 of California, have invented certain new and useful Improvements in Paint Guns, of which the following is a specification.

The present invention relates to that type of devices employed for spraying or applying liquids by air under pressure, and which devices are known to the trade under the common names of air brushes or paint guns.

The invention consists broadly in a hand-piece into which are led conduits or channels through which are supplied fluids under pressure, one preferably being in the form of a liquid, and within which the fluids are intermixed in controlled proportions and are discharged as an atomized product.

20 Among the objects of this invention is the provision of a novel type of discharge tip enabling the application of a flat stream of thoroughly and uniformly mixed material of any desired width or volume to a surface at low pressure, enabling the positioning of the nozzle in close proximity to the work, thus eliminating splashing or spray waste and affording a material saving in material and insuring the impregnating of 25 the surface to be coated with the material.

Another object is the provision of a novel form of control, whereby the material and conveying and atomizing agent may be independently varied to admit of the correct respective proportions of each as may be desired to enter the mixing chamber to be thoroughly intermixed therein prior to discharging in spray form from the nozzle tip.

40 A further object is to provide a construction which is light in weight, compact and easy to clean, and which is equipped with but few controls, capable of being readily adjusted by the operator on the job without the necessity of the operator returning 45 to the source of material supply for adjusting its flow therefrom.

With the above mentioned and other objects in view, the invention consists in the novel construction and combination of parts 50 hereinafter described, illustrated in the accompanying drawings, and set forth in the claims hereto appended, it being understood that various changes in the form, proportion, size and minor details of construction within 55 the scope of the claims may be resorted to without departing from the spirit or

sacrificing any of the advantages of the invention.

To more fully comprehend the invention reference is directed to the accompanying 60 drawings, wherein:

Figure 1 is a view in side elevation partly in section of the preferred embodiment of my invention.

Figure 2 is a view in end elevation of the 65 apparatus illustrated in Figure 1.

Figure 3 is a sectional view taken through the controlling valve on line 3—3 of Figure 1 viewed in the direction of the arrow.

Figure 4 is a transverse section on line 70 4—4 of Figure 1 viewed in the direction of the arrows.

Figure 5 is a view in detail section of the united valves for simultaneously controlling the inlet channels, the view being taken on 75 line 5—5 of Figure 1, viewed in the direction of the arrows.

Figure 6 is a fragmentary detail sectional view taken on line 6—6 of Figure 3, and

Figure 7 is a similar view taken on line 80 7—7 of Figure 3.

Figure 8 is a longitudinal sectional view of the tip removed from the nozzle.

Figure 9 is a view in plan of the tip core, and

Figure 10 is a similar view of the domed discharge tip illustrating the transverse discharge slot therein.

Referring more particularly to the several views of the drawings wherein like characters of reference designate corresponding parts, 1 indicates a hand-piece preferably formed with a solid head 2, and separable stock plates 3, united together by screws or other fastening means 4 to form a hand 95 grip. Within registering grooves 5 disposed longitudinally between the meeting faces of the pieces 3 are received the tubes or pipes 6 and 7, the pipe 6 being adapted for conducting air under pressure and the pipe 7 being adapted for conducting a liquid under 100 pressure.

In the present embodiment, the liquid referred to is preferably paint. The head 2 is formed interiorly with the parallel inlet 105 channels 8 and 9, which are connected by a transverse channel hereinafter termed an outlet channel 10, which extends interiorly through the end of the head 2. The channel 8 preferably connects with the air inlet pipe 110 6 and the channel 9 connects with the liquid inlet pipe 7, the channel 8 discharging into

the outlet channel 10 through a port 11 and the channel 9 discharging into the outlet channel 10 through a port 12. The outer end of outlet channel 10 provides a main mixing chamber for the fluids admitted through pipes 6 and 7. The passage of the fluids through the pipes 6 and 7 into the channels 8 and 9 is controlled by a valve structure mounted within a transverse recess 13 formed in the head 2 between the ends of the respective pipes and the channels 8 and 9, and into which said pipes discharge in forcing the material conveyed thereby into the respective channels 8 and 9. Within this transverse bore 13 is mounted to reciprocate the valve members 14, which are of a diameter to snugly fit the interior diameter of the bore 13. The members 14 are connected in spaced relation by a stem 15, and are so spaced so that one will overlie the end of the respective pipes 6 and 7, as in Figure 5. An operating handle 16, connected to the valves by the reduced stem 17, is positioned exteriorly of the handpiece 1 to be readily gripped by the fingers of the operator and forced inwardly when the operator grasps the hand-piece. A spring 18, retained under tension within a cup 19 and bearing against the end of the inner valve 14 normally maintains said valves in a position to close the discharge ends of said pipes 6 and 7 and in contact with a retaining pin 20 passing transversely across the bore 13. It will be observed that the inward movement of this pair of valves 14 causes a corresponding opening of the discharge ends of the pipes 6 and 7, to admit of the passage therefrom of material conveyed into the channels 8 and 9. The volume of material admitted into the channel 9, which, as previously explained, is preferably paint, is adapted to be further controlled by an auxiliary valve 21 which extends into the channel 9, and which at its point of intersecting the channel is provided with transverse cutout or depression 22. The valve is threaded within an opening 23 in the side wall of the head 2, and a packing gland 24 prevents the escape of paint around the same. A slight rotation of the valve 21 varies the area of the channel 9 at its point of passage therethrough and controls the paint or liquid adapted to be forced through said cutout or depression 22.

Over the discharge end of the outlet 10 is removably positioned a suitable atomizing or spray tip, and the same consists of an annular shell 25 adapted for reception within the discharge end of the outlet channel 10, and said shell 25 is provided with a dome discharge tip end 26, transversely slotted as at 27 and provided with the exterior shoulder 28 and the interior shoulder 29, illustrated in Figure 8. Removably fitted within the dome discharge tip 25 and

adapted for reception within the discharge end of the outlet channel 10 is a cylindrical core 30, provided with an annular shoulder to receive the shoulder 29 of the tip 25, and said core is provided with the conical discharge port 31 terminating at its apex in the contracted outlet 32 which discharges into the transverse slot 33 formed in the rounded projection 34 of the core which is received within the inner recess 35 of the dome 26. The recess 35 is adapted to afford a final mixing chamber for the material to be sprayed, and the transverse slot 27 insures the discharging of the material from the tip in a flat stream of the desired volume and width depending upon the adjustment of the controlling valves.

A needle valve 36 is mounted in the outlet channel 10 and the needle end 37 thereof is adapted to coact with the tapered wall of port 31 and control the mixed fluid volume adapted to pass through said tip. The body of the valve 36 which is of a normal diameter to snugly fit the walls of the recess 10 is annularly grooved as at 38 and 39 at points to normally overlie the discharge ends of channels 11 and 12. The valve body is longitudinally grooved at a single point between the annular grooves 38 and 39, as at 40, and the needle end thereof between the groove 39 and the point 37 is longitudinally grooved at a number of places, as at 41. The groove 40 permits passage of the air volume adapted to pass longitudinally of the needle valve to intermix with the paint which passes upwardly through the channel 12 into the annular groove 39 in the needle valve.

The limited air pressure admitted through groove 40 causes a withdrawal of the paint from the channel 12 and forces the same through the grooves 41.

It will be understood that the valve 36 in its adjustment controls the size and character of spray discharged from the domed discharge tip 26.

By my present construction, I have found it necessary and essential in obtaining a flat flaring discharge stream from the nozzle tip to provide a chamber 35 between the tip and core, as if this chamber is not provided, the desired result is not obtained.

Having thus described my invention what I claim as new and desire to protect by Letters Patent of the United States is:—

1. A liquid applying apparatus including a hand-piece provided with independent channels, a mixing chamber in the hand piece into which said channels discharge, a bulbous discharge tip at the discharge end of said mixing chamber and formed with a single discharge slot extending entirely across the same, and means for controlling the passage of fluid through said channels.
2. A liquid applying apparatus including

a hand-piece provided with independent channels, a mixing chamber in the hand piece into which said channels discharge, a discharge tip at the discharge end of said mixing chamber having a spheroidal end, 5 said tip provided on its interior with a hollow domed chamber, the spheroidal wall of said chamber being formed with a single transverse slot providing a discharge opening, and means for controlling the passage 10 of fluid through said channels.

3. A liquid applying apparatus including a hand-piece provided with independent channels, a mixing chamber in the hand 15 piece into which said channels discharge, a hollow bulbous tip over the discharge end of said chamber, said tip provided in its wall with a single transverse discharge slot extending entirely across the same, a core removably positioned within said the inner 20 surface of the wall of said bulbous tip with its wall in spaced relation to said tip, said core provided with a single outlet port, and means for controlling the passage of fluid 25 through said channels.

4. A liquid applying apparatus including a hand-piece provided with a pair of independent inlet channels and an outlet channel into which said inlet channels discharge, 30 said outlet channel provided with a discharge orifice, a slotted discharge tip over said discharge orifice, a needle valve within said outlet channel for controlling the discharge of material through said tip, 35 a valve within one of said inlet channels for controlling the maximum fluid passage therethrough, and a pair of connected valves one within each inlet channel and adapted for simultaneous operation on the 40 gripping of the hand-piece.

5. A liquid applying apparatus including a hand-piece provided with a pair of independent inlet channels and an outlet channel into which said inlet channels discharge, 45 said outlet channel being provided with a conical discharge orifice, a needle valve within said outlet channel and disposed with its outer end adapted for reception within said conical discharge orifice, said 50 valve provided with a pair of annular depressions one for movement into register with the discharge end of each of said inlet channels, said valve provided with a groove connecting said depressions, and with a second groove connecting one of said depressions with the needle end of said valve.

6. A liquid applying apparatus including a hand-piece provided with independent inlet channels and an outlet channel at sub- 55 stantially right angles thereto and into

which the same discharge, said outlet channel provided with a discharge port at one end, a discharge tip associated with said ported end and provided with a discharge orifice, and a needle valve within said outlet channel adapted for adjustment to control the passage of material through said discharge orifice, the body of said valve at a point inwardly from said needle point being cut to provide a pair of conical depressions 65 disposed with their apices toward each other in spaced relation, said valve body between said conical depressions and between the outer of said depressions and said needle point being longitudinally grooved. 70

7. A liquid applying apparatus including a hand-piece provided with independent inlet channels and an outlet channel at substantially right angles thereto and into which the same discharge, said outlet channel provided with a discharge port at one end, a discharge tip associated with said ported end and provided with a discharge orifice, a needle valve within said outlet channel adapted for adjustment to control 75 the passage of material through said discharge orifice, the body of said valve at a point inwardly from said needle point being cut to provide a pair of conical depressions disposed with their apices toward each other in spaced relation, said valve body between 80 said conical depressions and between the outer of said depressions and said needle point being longitudinally grooved. 85

8. A liquid applying apparatus including a hand-piece provided with a pair of independent channels and an outlet channel into which the same discharge, said outlet channel being provided with a discharge orifice, valve mechanism provided with a needle end 100 and positioned within said outlet channel for controlling the discharge through said orifice, a discharge tip associated with said orifice and including a hollow body provided with a domed end and formed with a transverse discharge slot, and a cored member 105 removably fitted within said body with its outer surface in spaced relation to the domed end of said tip, said core provided with a tapered orifice in line with said discharge 110 slot and within which said needle end is adapted to co-operate.

In testimony whereof I have signed my name to this specification.

JOHN D. MURRAY.
